UNITED STATES PATENT OFFICE

LORING WASHBURN, OF GREENWICH, CONNECTICUT, ASSIGNOR TO S. H. POMEROY COMPANY, INC., OF NEW YORK, N. Y., A CORPORATION OF NEW YORK

RADIATOR SUPPORT

Application filed November 3, 1927. Serial No. 230,744.

This invention has for its object to provide for steam radiators and the like such means of support as shall obviate the necessity of permitting the radiators to stand on the floor. It has been proposed heretofore to support such radiators by brackets which are directly engaged with the sills of metal window frames. This is not wholly satisfactory, involving as it does special construction of the sills, and it has been the special purpose, in the development of the present invention, to provide for the support of a radiator clear of the floor by means which not only shall require no special construction 15 of the sill or other part of the window frame, but shall be, in fact, capable of use, if so desired, independently of a window frame, although radiators are commonly associated with window openings. In accordance with 20 the invention there is provided a relatively heavy and stiff metal plate which may be built into a building wall, in association with a window opening or otherwise as conditions may require, such plate being adapted to support brackets by which the radiator is supported. Provision is also preferably made 25 whereby the varying thickness of plaster on the wall and other differing factors of building construction can be accommodated, so 30 that a radiator shall be supported in proper relation to the inner face of the wall. The invention will be explained more fully hereinafter with reference to the accompanying drawing in which it is illustrated and in 35 which:

Figure 1 is a partial view in elevation showing a portion of a window frame and the means for supporting a radiator in desired relation therewith, the building wall being 40 also indicated.

Figure 2 is a view of the supporting device as seen from above, a window frame being also shown in horizontal section.

Figure 3 is a detail view in sectional elevation on the plane indicated by the broken line 3-3 of Figure 1.

In the embodiment of the invention illustrated in the drawing, a relatively heavy and stiff anchor plate *a* of metal is provided, the 50 dimensions being such that it can be built

into the building wall as the construction of the wall progresses. As the radiator is generally associated with a window opening, the plate *a* is conveniently laid upon the masonry which forms the bottom of the window opening in the building wall and is extended beyond the sides of such opening into the wall as indicated at *a*¹ being thereby held securely in place. The window frame *b*, of metal or otherwise, may rest upon such plate *a*, and for convenience in assembling and setting up the job the window frame may be secured to the plate *a*, at least temporarily, by angles *c* secured to the window frame and the plate *a* by screws *c*¹. The edge of the plate *a* may be turned down, as at *a*² for the purpose of stiffening it. The wall *d* is usually faced on the inner side with plaster, as at *d*¹, and as the thickness of plaster may vary it is desirable to provide for the plate *a* an adjustable supporting plate or portion *a*³, which may be secured adjustably to the plate *a* by screws *a*⁴ which pass through slots *a*⁵ formed in the adjustable portion *a*³ and be threaded into the plate *a* or into nuts *a*⁶ on the underside 55 of the plate *a*. The adjustable portion *a*³ has its inner edge turned up, as at *a*⁷ for the purpose of stiffening the plate and also for convenient engagement by the brackets *e*. The latter are shown as composed each of 60 two members *e*¹ and *e*² of relatively heavy sheet metal. Member *e*⁵ is formed at its upper end with a hook *e*³ for engagement with the supporting plate *a*³ and is arranged to lie flat against the wall *d*¹. The member *e*² 65 is secured to the member *e*¹ in any convenient manner, as by a tongue and slot connection as indicated at *e*⁴, and is arranged to project inwardly from the building wall to support the radiator as indicated in the drawing. 70 The brackets *e* are free to slide on the supporting plate and can, therefore, be shifted readily to accommodate radiators of different constructions.

I claim as my invention:

1. A combination of a wall having a window opening, a metal window frame mounted in said opening, a relatively heavy and stiff plate of metal independent of the window frame, interposed between the window frame 75 and

and the bottom of the window opening in the wall and extended longitudinally of the window opening, a plate adjustably secured to the first named plate and having an upturned edge, and radiator supporting brackets provided at their upper ends with hooks to engage the upturned edge of the second named plate and movable longitudinally with respect thereto.

2. A device of the character described comprising an anchor plate, extensions thereon to be imbedded in a supporting structure, a supporting plate mounted at one side thereof, means to secure the supporting plate adjustably to the anchor plate, a turned up portion on the supporting plate, and means to engage the turned up portion to support a radiator thereon.

3. A radiator support comprising a supporting plate composed of two portions, one of said portions being adapted to be built into a building wall, securing means on one of the portions, means on the other portion to engage the first portion in a plurality of positions, means to secure the engaging portions together in engaged position, an upturned edge on one of the portions, and radiator supporting brackets formed with hooks to engage the upturned edge of the said last named portion and adapted to be moved longitudinally thereon.

4. A radiator support comprising a supporting plate composed of two portions, one of said portions being adapted to be built into a building wall, screw threaded means on one of the portions, a slot on the other portion engaging the screw threaded means whereby the last named portion may be secured in a plurality of positions, an upturned edge on the last named portion, and radiator supporting brackets formed with hooks to engage the upturned edge of the last named portion and adapted to be moved longitudinally thereon.

45 This specification signed this 1st day of November, A. D. 1927.

LORING WASHBURN.
